UNITED STATES PATENT OFFICE.

CHARLES B. PENNELL, OF DUNCANNON, PENNSYLVANIA.

DESIGN FOR A GAME-BOARD.

SPECIFICATION forming part of Design No. 33,057, dated August 14, 1900.

Application filed July 2, 1900. Serial No. 22,369. Term of patent 14 years.

To all whom it may concern:

Be it known that I, CHARLES B. PENNELL, a citizen of the United States, and a resident of Duncannon, Perry county, Pennsylvania, have invented and produced a certain new and original Design for a Game-Board, of which the following is a specification.

My design for a game-board is fully shown in the accompanying drawing, which represents a face view of the board.

The essential features of the design are the central "home" space with six equidistantly-disposed alleys radiating therefrom and separated from each other by outwardly-flaring spaces.

In the drawing, 1 represents the central home space, 2 the radiating alleys, and 3 the intervening outwardly-flaring spaces. Each of the radiating alleys has parallel sides and

is divided by parallel radial and right-angled transverse lines into three suballeys, each having a series of rectangular spaces, some of which are shaded so as to form circular spots in the same manner as those of an ordinary pachisi-board. The innermost spaces of each alley are extended laterally so as to join those of the next alley.

Having thus described my invention, I claim and desire to secure by Letters Patent—

The design for a game-board, substantially as described and shown.

In testimony whereof I have signed my name to this specification in the presence of two subscribing witnesses.

CHARLES B. PENNELL.
